CLAIM

The ornamental design for a multiport for making optical connections, as shown and described.

DESCRIPTION

FIG. 1 is a front perspective view of a multiport for making optical connections showing our new design;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.

In FIGS. 1-7, the dash-dash broken lines illustrate portions of the article that form no part of the claimed design. In FIGS. 1, 2, and 4-7, the dash-dot broken lines are for the purpose of illustrating the bounds of the claim and form no part of the claimed design.
